UNITED STATES PATENT OFFICE

151,474

DESIGN FOR A MICROFILM-READER CASING

Nathan Sally Stern, New York, N. Y., assignor to
American Measuring Instruments Corporation,
New York, N. Y.

Application May 4, 1946, Serial No. 129,342

Term of patent 3½ years

(Cl. D61—1)

To all whom it may concern:

Be it known that I, Nathan Sally Stern, a former citizen of Germany, now without nationality, residing at New York, in the county of New York and State of New York, have invented a new, original, and ornamental Design for a Microfilm-Reader Casing, of which the following is a specification, reference being had to the accompanying drawing, forming part thereof.

Fig. 1 is a perspective view of a microfilm-reader casing, showing my new design.

Fig. 2 is an end view of the opposite end, not shown in Fig. 1 but on a greatly reduced scale, and

Fig. 3 is a perspective view of the article in an open condition.

I claim:

The ornamental design for a microfilm-reader casing, as shown.

NATHAN SALLY STERN.
